UNITED STATES PATENT OFFICE.

FERDINAND SPANINGER, OF STUTTGART, GERMANY.

GARMENT SUSPENDER OR HOLDER.

No. 850,405.

Specification of Letters Patent.

Patented April 16, 1907.

Application filed October 8, 1906. Serial No. 338,073.

15 *all whom it may concern:*

Be it known that I, FERDINAND SPANINGER, a citizen of the German Empire, residing at Stuttgart, in the Kingdom of Würtemberg, Empire of Germany, have invented certain new and useful Improvements in Garment Suspenders or Holders, of which the following is a description, reference being had to the accompanying drawings, and to the letters and figures of reference marked thereon.

This invention relates to garment supporting and adjusting devices, and has for its principal object to provide a device of simple construction by which the length of a garment or a portion thereof may be increased or diminished to suit the convenience of the wearer.

A further object of the invention is to provide a device of this type in which the parts are so constructed as to exercise a frictional grip which will support the weight of the garment while at the same time permit of ready and immediate adjustment.

With these and other objects in view, as will more fully hereinafter appear, the invention consists in certain novel features of construction and arrangement of parts herein-after fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a front elevation of a garment supporting and adjusting device constructed in accordance with the invention. Fig. 2 is a side elevation of the same, and Fig. 3 is a view similar to Fig. 1 with the parts fully contracted.

Similar numerals of reference are employed to indicate corresponding parts throughout the several figures of the drawings.

The device includes a pair of U-shaped end members *a* *b*, each of which is provided with an eye *e* at one end for engagement with a stud *a'*, the stud being preferably provided with openings for the passage of thread, so that they may be readily sewed to portions of the garment—for instance, to a skirt. The ends of the two members *a* and *b* are coiled to form closed helices *c*, which surround the arms *d* of an intermediate frame,

said frame being preferably formed of a piece of wire bent upon itself to provide further parallel arms, the two coils of the upper member *a* being arranged to slide upon and to frictionally grip the inner pair of arms, 60 while the terminal helices *c* of the lower member are arranged to slide upon and grip the outer arms, while the ends of such outer arms are bent inward, as indicated at *f*, in order to prevent the complete withdrawal of the 65 lower member from the intermediate frame.

The device is of such construction that the helices may frictionally grip the arms or bars *d* and cannot be accidentally moved by the weight of the garments, while at the same 70 time they may be slid upon the frame *d* to increase or decrease the distance between the attaching-studs, and thus alter the length of the garment.

The device, while of use in connection with 75 garments of all types, is of especial value for adjusting the length of women's skirts, and by sewing the same either inside or outside the skirt the wearer may raise or lower the hem, as desired.

Having thus described my invention, what I claim as new, and desire to secure by Letters Patent, is—

1. A garment supporting and adjusting device, including a plurality of slidably-engaging members having terminal coils which serve to bind and hold the sections in adjusted position; substantially as described. 85

2. In a device of the class described, end members having terminal coils and adapted 90 for attachment to a garment, and an intermediate frame having arms on which said coils may slide, the coils serving to grip the arms and retain the parts in adjusted position; substantially as described. 95

3. In a device of the class described, a pair of end members having eyes at one end, member-attaching studs extending through said eyes, the adjacent ends of said members being turned to form closed helices, and an 100 intermediate frame having four parallel arms which are surrounded and grouped by said helices; substantially as described.

In testimony whereof I affix my signature in presence of two witnesses.

FERDINAND SPANINGER.
